Patented Sept. 28, 1920.

FIG. 1.

FIG. 2.

UNITED STATES PATENT OFFICE.

NATHANIEL A. STRATTON, OF BOSTON, MASSACHUSETTS.

CRUSHING AND PULVERIZING MACHINE.

1,854,077.

Specification of Letters Patent. Patented Sept. 28, 1920.

Application filed September 15, 1919. Serial No. 323,357.

To all whom it may concern:

Be it known that I, NATHANIEL A. STRATTON, citizen of the United States, residing at Boston, in the county of Suffolk and State of Massachusetts, have invented new and useful Improvements in Crushing and Pulverizing Machines, of which the following is a specification.

This invention relates chiefly to a machine for crushing and pulverizing metal-bearing ores and other analogous material by the conjoint action of two crushing jaws, one of which is power-driven. The object of the invention is to provide a machine, the power-driven jaw of which is moved progressively in a continuous circular path, so that the machine is adapted to operate continuously and more rapidly than a machine, the power-driven jaw of which has a reciprocating motion. The invention is embodied in the improvements which I will now proceed to describe and claim.

Of the accompanying drawings, forming a part of this application,—

25 Figure 1 is a vertical central section of a machine embodying the invention.

Fig. 2 is a section on line 2—2 of Fig. 1, parts being broken away.

The same reference characters indicate the same parts in all of the figures.

In the drawings, 12 represents a hollow pedestal forming the chief portion of the base of the machine. 13 represents a horizontal bottom plate fixed to the upper portion of the pedestal and forming another portion of the base. The plate 13 has a central opening 14, the wall of which is recessed to form a ball race portion 15 containing a circular series of balls 16, which are confined against vertical displacement by confining ring 17 screwed to the plate 13.

The balls 16 collectively constitute an annular antifrictional fulcrum on which a lever is adapted to swing or oscillate universally to a limited extent. Said lever is composed of a longer arm 18 below the fulcrum and a shorter arm 19 above the fulcrum, the line of demarcation between said arms being an annular shoulder 20, which is the portion of the lever contacting with the annular fulcrum.

The shorter arm 19, which may be of any suitable metal, such as chrome steel, is frusto-conical and constitutes a crushing jaw to which swinging and revolving movements are imparted, through the longer arm

18, by a driving member 21, which rotates on a center 22 coaxial with the annular fulcrum. In other words, the axis of the member 21, if prolonged, would pass through the center of the space surrounded by the balls 16. The member 21 has an eccentrically arranged socket 23, which receives the lower end of the longer arm 18. Said member is preferably secured by bolts 24 to the hub of a pulley 25 journaled to rotate on a fixed stud forming the center 22 above mentioned, the pulley being rotated by a driving belt 26.

27 represents an annular jaw, preferably of chrome steel, surrounding the conical jaw 19 and secured to the base of the machine in such manner that while it is normally coaxial with the driving member 21 and with the annular fulcrum, it is movable laterally with relation to the conical jaw. The annular jaw 27 is yieldingly held in its normal position by radial springs 29 supported by fixed abutments 30 on the base and segmental brake shoes 31 pressed by said springs against the annular jaw.

The springs 29 and shoes 31 are confined against upward displacement by a top plate 32 secured to the pedestal by bolts 33, said bolts passing through a spacing plate 34 resting on the bottom plate 13 and forming a part of the base, said spacing plate having a central opening and slots radiating therefrom, the outer ends of which form the spring abutments 30, and a central opening containing the shoes 31. The annular jaw 27 is vertically adjustable and is provided at its upper end with ears 36, having bearing screws 37 resting on a horizontal annular upwardly facing seat 38 on the top plate 32. Adjustment of the screws raises or lowers the annular jaw. The bearing screws slide laterally on the seat 38 when the annular jaw is moved laterally.

On the top plate 32 is a fixed hopper 40 having a flexible funnel-shaped annulus 41, constituting an extension of the guiding surface of the hopper, said annulus 41 overlapping and resting loosely on the upper end of the annular jaw 27 and permitting horizontal yielding movements of said jaw and preventing material in the hopper from entering the spaces or crevices outside the annular jaw. Said annulus is preferably of flexible material, so that it is apt to conform freely to horizontal movement of the annular jaw, a suitable material being sheet

lead. The annulus may be clamped between a ring 42 and a shoulder formed on the hopper, the ring being attached to the hopper by screws 43. The ring and annulus 5 may be detached from the hopper to permit access to the adjusting screws 37.

A tapering annular material-receiving throat 44 is formed by the external surface of the conical jaw and the internal surface 10 of the annular jaw. Material falling into this throat from the hopper is crushed and pulverized by the two jaws. The jaw 19 is moved progressively in a continuous circular path by the action of the driving member 21 on the longer arm 18, the movement 15 of the jaw being such that the throat 44 is progressively contracted by the movements of the conical jaw, said movements causing the jaw to successively assume the different 20 positions shown by full and dotted lines in Fig. 1. The action is continuous and the material is thoroughly pulverized when it reaches the lower end of the throat 44. The pulverized material passes through outlets 25 46 in the plate 18, to an inclined chute 47 extending through one side of the pedestal 12. The chute has an opening 48 through which the lever arm 18 passes, and an upwardly projecting sleeve 49 formed to prevent the falling material from entering the 30 opening 48.

The object of the lateral yielding movement of the annular jaw is to prevent excessive strain on the two jaws when relatively 35 large pieces are being crushed. A large piece wedged in the crescent-shaped space between the jaws transmits movement from the gyrating conical jaw to the annular jaw, causing the latter to yield. The segmental 40 brake shoes 31 have extended frictional contact with the external surface or periphery of the annular jaw and prevent the latter from turning, while permitting it to yield in a rectilinear direction. If a turning 45 movement of the annular jaw were permitted, a relatively large piece wedged, between the surfaces of the jaws would be carried around with the gyrating conical jaw without being crushed. The vertical adjustability of the annular jaw enables the 50 fineness of the pulverization to be varied.

I claim:

1. A crushing machine comprising a base having a central annular fulcrum and fixed 55 spring abutments spaced outwardly from said fulcrum, a lever adapted to oscillate universally on said fulcrum and having, below the fulcrum, a longer arm, and, above the fulcrum, a shorter conical arm constituting a conical crushing jaw, an annular crushing jaw surrounding the conical jaw, and adapted to slide horizontally on the base in any direction, said jaws forming a tapering annular throat, means for gyrating said 60 lever on its annular fulcrum to cause a

progressive contraction of said throat, springs radiating from the annular jaw and seated at their outer ends on said abutments, and segmental brake shoes pressed by said springs against the external surface of the 70 annular jaw, said springs and brake shoes permitting horizontal rectilinear yielding movements of the annular jaw, and preventing a turning movement of the annular jaw by force transmitted from the gyrating conical jaw through material wedged in said throat.

2. A crushing machine comprising a base having a central annular fulcrum, fixed spring abutments spaced outwardly from 80 said fulcrum, and a horizontal upwardly facing annular seat concentric with said fulcrum; a lever adapted to oscillate universally on said fulcrum and having a longer arm below the fulcrum and a conical shorter arm above the fulcrum, constituting a conical crushing jaw, an annular crushing jaw surrounding the conical jaw and surrounded by said seat, the annular jaw being provided with bearing members 85 which are slidable horizontally on said seat and are vertically adjustable to vary the height of the annular jaw relative to the conical jaw, said jaws forming a tapering annular throat, means for gyrating said 90 lever on its annular fulcrum, to cause a progressive contraction of said throat, springs radiating from the annular jaw and seated at their outer ends on said abutments, said springs permitting horizontal rectilinear yielding movements of the annular jaw, an annular hopper fixed to the base and provided with a flexible funnel-shaped annulus, detachably secured at its upper 95 edge to the hopper, and constituting an extension of the guiding surface of the hopper, the lower edge of said annulus overlapping and bearing loosely on the outer end of the annular jaw, so that said jaw is in sliding contact with the annulus and receives material guided by the latter in any 100 position to which said jaw is movable, the detachability of the annulus from the hopper permitting the displacement of the annulus to permit access to and adjustment of 105 the said bearing members.

3. A crushing machine comprising a base including a fixed plate having a central opening, the wall of which is recessed to form a ball race portion containing a circular series of balls constituting an anti-frictional annular fulcrum, said plate being also provided with a confining ring projecting over said balls, the base being provided with fixed spring abutments spaced outwardly from said fulcrum, a lever having an annular shoulder partly overhanging the fulcrum formed by said balls and supported thereby, said lever having a longer arm below said shoulder, and a shorter conical arm 110 115 120 125 130

above the shoulder constituting a conical crushing jaw, an annular crushing jaw surrounding the conical jaw and adapted to slide horizontally on the base in any direction, said jaws forming a tapering annular throat, means for gyrating said lever on its fulcrum to cause a progressive contraction of said throat, and radial springs interposed between said abutments and the annular jaw 10 and normally maintaining said jaw in a central position from which it is adapted to yield horizontally.

4. A crushing machine comprising a base including a hollow pedestal, a horizontal bottom plate fixed to the upper end of the pedestal, and provided with a central opening, the wall of which is recessed to form a ball race portion containing a circular series of balls constituting an anti-frictional 15 20 annular fulcrum, said plate being also provided with a confining ring projecting over said balls, a fixed spacing plate superimposed on said bottom plate and provided

with a central opening and slots radiating therefrom and providing spring abutments, 25 and a fixed top plate superimposed on the spacing plate and provided with a central opening, an annular crushing jaw adapted to slide horizontally on said top plate, and located in the openings of the top plate and 30 spacing plate, radial springs located in the slots of the spacing plate and normally maintaining the annular jaw in a central position from which it is adapted to yield horizontally, a lever having an annular 35 shoulder partly overhanging the fulcrum formed by said balls and supported thereby, said lever having a longer arm below said shoulder, and a shorter conical arm above the shoulder constituting a conical 40 crushing jaw which is surrounded by the annular jaw and means for gyrating said lever on its annular fulcrum.

In testimony whereof I have affixed my signature.

NATHANIEL A. STRATTON.
